FIG. 13.

UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 903,481.

Specification of Letters Patent. Patented Nov. 10, 1908.

Application filed March 16, 1908. Serial No. 421,892.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

My invention relates especially to ribbon mechanisms for typewriting machines, and its object generally stated is to provide improved devices of the class specified.

To the above and other ends, the invention consists in the features of construction, combinations of devices and arrangements of parts hereinafter described and particularly pointed out in the claims.

My invention is shown as applied to a front-strike typewriting machine of the shifting platen style or type, but the nature of the invention is such that it may be adapted to other kinds of writing machines.

One form of the invention is illustrated in the accompanying drawings, wherein—

Figure 1 is a vertical front to rear sectional view of a typewriting machine embodying my invention, said view being taken about centrally of the machine, various parts of said machine being omitted. Fig. 2 is a sectional view taken on the plane represented by the dotted line α in Fig. 1 and looking in the direction of the arrow at said line, parts of the machine being broken away and parts omitted. Fig. 3 is an enlarged fragmentary sectional view corresponding in part to Fig. 1 and showing details of the ribbon mechanism, certain of the parts being in different relations from those in which they appear in Fig. 1. Fig. 4 is a top view partly in section of the ribbon operating lever and certain of the associate parts. Figs. 5 to 8 inclusive are diagrammatic views illustrating various relations between the printing portion of the ribbon and the platen when the upper edge portion of the ribbon is being employed. Figs. 9 to 12 are corresponding views to Figs. 5 to 8 but showing the relations between the printing portion of the ribbon and the platen when the lower edge portion of the ribbon is being employed. Fig. 13 is a diagrammatic plan view illustrating the means for feeding the ribbon longitudinally together with part of the vibrator controlling means. Fig. 14 is a side view partly in section showing the hand operated devices for actuating the mechanism controlling a part hereinafter called an actuating link. Fig. 15 is a side view of a modification.

Referring first more especially to Figs. 1 and 2, the main frame of the machine is shown as comprising a base 1, corner posts 2 and a top plate 3. Key levers 4 are fulcrumed at 5 at the rear of the base, each key lever being provided with a restoring spring 5^a and being connected by suitable actuating devices 6 (not shown) with a type bar 6, the set of type bars being supported on a segmental support 7, said support in the present instance being stationary and suitably secured to the frame of the machine. The type bars are each provided with an upper case type 6^a and a lower case type 6^b and when actuated are adapted to coöperate with the front face of the platen 8 which is rotatable in a frame or carrier presently to be described, said carrier being shiftably mounted on a carriage comprising side bars 9 and front and rear bars numbered respectively 10 and 11. The front and rear bars are grooved to coöperate with anti-friction balls 12, said balls also coöoperating with grooved front and rear guide rails numbered respectively 13 and 14 which are fixed to the frame of the machine above the top plate. The carriage is suitably connected with a spring drum 15 (diagrammatically shown in Fig. 13), which constantly urges the carriage leftward, the leftward movement being controlled by suitable letter feed devices not shown, certain of said letter feed devices being connected to a link 16 which extends downward and is pivoted at its lower end to the horizontal arm of a bell crank lever 17 fulcrumed at 18 to an arm 19 extending downward and rearward from the segmental support 7 to which said arm 19 is fixedly secured by a screw 20. The vertical arm of the bell crank 17 is connected by an adjustable link 21 to a crank arm 22 fixed to and extending upward from a rock shaft 23, said rock shaft being pivoted on screw pivots 24 supported in the sides of the base 1. Near its ends the rock shaft is provided with rearwardly extending arms 25 from which depend arms or links 26 carrying a universal bar 27 underlying the key levers. When one of the latter is actuated to operate its associate type bar the universal bar will be operated to cause the letter feeding devices to coöperate to permit the carriage to be moved.

moved a letter space towards the left under the influence of the spring drum 15.

The platen is provided with an axle 28 which is mounted in a carrier comprising 5 end bars or plates 29 connected by a cross bar 30, which end bars are pivotally connected by links 31 with the side bars 9 of the carriage. A roller 32 mounted at the front of the bar 30 coöperates with a shiftable 10 guide rail 33 which is supported near its ends on upright rods 34 movable through openings in the top plate, said rods being fixed to and rising from a cross bar 35. Said cross bar in turn is carried by vertical rods 36 15 each pivotally connected at 37 with a shift lever 38 pivoted on a rock shaft 39 intermediate its ends and terminating at the front of the machine in a key button 40. During the travel of the carriage back and forth 20 across the top plate the relation of the plate 8 and platen carrier with said carriage will ordinarily remain unaltered, the roller 32 running back and forth over the shift rail 33. If, however, it be desired to print in upper 25 case, one of the shift keys 40 may be depressed, thus raising the shift frame comprising the rods 36, cross bar 35, rods 34 and shift rail 33, and thereby raising the platen carrier and platen to upper case position. 30 Stops 35^a and 35^b operate to limit the shifting movements of the platen. Except for the connection between the crank arm 22 and the escapement devices (said connection comprising the bell crank 17, its sup- 35 port and the links connected with said bell crank), the parts above described are not original with me and are not claimed herein, save in combination with other devices presently to be described.

40 A ribbon 41 is secured to and wound upon ribbon spools 42, said ribbon spools being vertically disposed beneath the top plate, one at each side of the machine and forward of the platen as shown in Figs. 1 and 2. Each 45 ribbon spool is secured to the forward end of a horizontal shaft 43 journaled in lugs depending from the top plate. Referring to the diagrammatic plan view (Fig. 13) it will be seen that the shaft 43 is provided at its 50 rear end with a beveled pinion 44 which is adapted to coöperate with a beveled driving pinion 45 secured to a driving or power shaft 46, the latter being connected with and adapted to receive motion from the spring drum 15 55 through a train of devices comprising beveled pinions 47 and 48, said pinions being constantly in mesh with each other. The pinion 48 is suitably connected with the spring drum when the latter turns to draw the carriage in printing direction and the pinion 47 is slidably connected with the driving shaft 46 so that without disengaging pinion 47 the shaft may be moved endwise to connect one or the other of the driving pinions 45 with its 60 associate pinion 44, thereby causing the asso-

ciate ribbon spool to be turned to wind the ribbon thereon. Any of the known or suitable means may be employed to connect the shaft 46 with the pinion 47 to cause the latter to turn said shaft while at the same time permitting independent endwise movement of said shaft.

Midway between the ribbon spools the ribbon 41 is threaded through a vibratory carrier or vibrator comprising a body portion 49 70 and two lateral hook-like extensions 50 which coöperate with the body portion to provide slots through which the ribbon passes in such a way that the printing portion thereof, or that portion between the slots, is maintained 75 in a vertical or substantially vertical position in a vertical or substantially vertical position and extends lengthwise of the platen. The vibrator is guided and supported on the upright arms of a bracket 51 which is secured to the top plate of the machine by screws 51^a. 80 The lower end of the stem 49^a of the vibratory carrier is bifurcated and carries a cross pin 52 which pivotally engages with an operating lever, which in the present instance comprises two parts jointed together and capable of relative movement with respect to each other. The construction of this operating lever is best shown in Figs. 3 and 4. The forward arm 53 of said lever is slotted at its forward end as indicated at 54 to coöperate with the cross pin 52 of the carrier. The rear end portion of the part 53 is retained in a slot 55 formed at the forward end portion of a bar-like member 56, which member is comprised in the rear part of the operating lever. 90 The parts of the operating lever are pivotally connected or jointed at 57, so that relative movement between the two parts may be had. In the present instance relative movement is obtained by swinging the part 53 on 95 the pivot 57 during platen shifting movements by means presently to be described and for purposes hereinafter explained. Besides the member 56, the rear part of the operating lever preferably further comprises a 100 member 58, the forward end whereof fits into a slot or kerf in the rear of the member 56, the two members 56 and 58 being secured together by means of rivets 59 or in any other suitable way. The member 58 is formed of 105 thinner stock than the member 56 as shown in Fig. 4, but said member 58, viewed from the side as in Fig. 3, is considerably wider than the member 56. It will of course be apparent that instead of being composed of two 110 members the rear part of the operating lever may consist of one member which may be made in the desired shape or form; and that the two parts of the operating lever instead of being in the same plane as shown may be in different parallel planes. The member 58 is received in a slot in a bracket or lug 60 depending from the top plate and is pivoted on a shouldered screw 61 which passes through 115 said lug from side to side and serves as a ful- 120

65 125 130

crum for the operating lever, considered as a whole. The end of the screw 61 opposite to the head thereof projects beyond the face of the lug 60 and is reduced as indicated at 62 5 (Fig. 4) for a purpose presently to be explained.

The rear portion of the member 58 behind the fulcrum 61 is formed with a slot 63 which receives a cross pin 64 (Figs. 1 and 2) carried 10 at the top of arms 65, said arms being formed by bifurcating the upper and wider portion of an actuating link, the stem 66 whereof is pivotally connected at 67 with the horizontal arm of the bell crank lever 17. The slot 63 15 is arcuate being struck from the pivotal point 67 of the actuating link as a center so that the pin or actuating device 64, carried at the upper end of said link, may when the link is swung longitudinally of the operating 20 lever, pass freely from one end of the slot 63 to the other. The pin 64 is constantly urged toward the rear end of the slot 63 by a draw spring 68, one end of which is secured to the stem 66 of the actuating link and the other 25 end to an arm 69 fixed to and extending vertically upward from the rear end portion of the arm 19.

The position of the pin in the slot is determined by a positioning member which coöperates with the forked or bifurcated upper portion of the actuating link. Said member is clearly shown in Figs. 1 and 2. It is mounted on the ribbon driving shaft 46 and comprises a circular disk-like part or face 70 35 concentric with the shaft 46, a second concentric disk-like part or face 71 of lesser diameter and an eccentric disk-like part or face 72, the greatest radius whereof corresponds with the radius of the disk 70 while 40 its least radius corresponds with the radius of the disk 71. The disk 71 is between the disk 70 and the disk 72 and is connected therewith by coned or cam parts or faces numbered respectively 73 and 74. The controlling member is grooved to receive a feather or spline 46^a which is fixed to the shaft 46 and connects said shaft and member so that the latter is forced always to rotate with the shaft but may be slid lengthwise 45 thereon so as to bring one or another of the disks 70, 71 and 72 into coöperation with the actuating link. To provide for this sliding movement of the controlling member on the shaft said member is provided with an extension or collar 75 which is formed with a circumferential groove 76, the latter coöperating with the forked upper end portion of an arm 77. Said arm forms part of a hand-operated means and has a hub portion 78 50 which is fixed to the inner end of a slide rod 79, that is supported on an inverted T-shaped bracket 80 depending from the top plate. The outer or right-hand end of the rod 79 carries a collar 81 in which is fixed a forwardly projecting horizontal pin 82.

Said pin engages in an elongated slot 83 formed at the upper end of a vertically disposed crank arm 84 fixed to a horizontal rock shaft 85 which is journaled at the rear on a bracket 86 fixed to the top of the base 1 at 70 the right-hand side thereof (Fig. 14). The rock shaft 85 extends forward through and bears in the right-hand front corner post and has fixed to its forward end an upwardly extending crank arm 87 provided with a handle 75 or finger piece 88 by which the crank arm 87 may be turned to give oscillatory movement to the rock shaft 85, slide the rod 79 back and forth and move the controlling member transversely of the actuating link. Any 80 other suitable means for moving the controlling member on the shaft 46 may be employed. Any suitable means may be provided to retain the hand operated means in one or another of a plurality of positions so 85 as to maintain the controlling member in predetermined relations with the actuating link. For example, the crank arm 87 may be provided with a rearwardly extending pointed lug 87^a which may engage with one 90 or another of three holes 89 formed in the corner post, the crank arm being sufficiently resilient to permit the withdrawal of the lug from engagement with one hole 89 so that the arm 87 and the parts connected therewith 95 may be moved until said lug engages with another one of the holes. Suitable indicating marks as "N", "B" and "R" may be provided on the corner post above the holes 89, and the crank arm 87 may be provided 100 with a coöperating pointer 90.

The parts are so arranged and proportioned that when the pointer 90 is opposite the mark "N", meaning normal, the eccentric disk 72 of the controlling member will be 105 in coöperation with the actuating link, the latter being maintained against said face by the draw spring 68. As the carriage is fed in letter space direction the controlling member will be slowly revolved by the ribbon 110 driving shaft 46, and the actuating link will be moved through the instrumentality of the eccentric disk 72 and the draw spring 68 back and forth lengthwise of the slot 63, causing the pin 64 to act on the rear arm of the operating lever at progressively varying distances from the fulcrum thereof when the printing keys are actuated. At such operation of the printing keys it will be understood that the actuating link will be drawn 115 downward, pulling down the rear arm of the ribbon vibrator operating lever. Assuming that the two arms of said operating lever are maintained in a fixed relation during this actuation, it will be understood that the ribbon carrier will be raised to present the printing portion of the ribbon opposite the printing point on the platen and that the extent to which the ribbon carrier is raised or 120 thrown will be progressively varied, causing 125 130

the types to follow a path extending lengthwise of the ribbon and curving or waving back and forth from one edge thereof to the other.

5 From a consideration of Fig. 1 it will be apparent that the eccentric disk 72 and the concentric disk 70 are arranged quite close to the rear end portion of the operating lever. In order to enable said lever to be vibrated 10 without being obstructed by the disks 72 and 70 when they are in operative position, said disks are respectively formed with circumferential grooves or depressions numbered respectively 72^a and 70^a, thus providing openings through which the end of the operating lever may move freely up and down.

The cross feed communicated to the ribbon in the manner above described by means comprising the eccentric disk 72 is especially 20 adapted for use with a ribbon of uniform character throughout and provides for thoroughly exhausting the inked surface of said ribbon. This cross feeding means may if desired be employed with a ribbon such as that shown in the drawings and numbered 41, which ribbon is divided into two longitudinal stripes or fields, marked *a* and *b*, of different characteristics. These stripes for example may be different in color, the field *a* being, say, black and the field *b*, red. Instead of employing the cross feed with a ribbon like 41 it is usually desired however to make use exclusively of one field or the other at pleasure, and the controlling member and 30 associate devices provide means for enabling this result to be accomplished. When, for example, it is desired to make use of the black field, the handle 88 is operated to position the pointer 90 opposite the indicating 40 mark "B", causing the hand operated devices to act on the controlling member so as to slide the latter on the shaft 46 until the face 71 is in engagement with the actuating link which will be drawn by its spring 68 rearward, causing the pin 64 to operate at 45 the rear of the slot 63, the normal position of the parts at this time being indicated in Figs. 1 and 2. The actuation of the printing keys when the parts are so positioned will operate to give the ribbon carrier its least extent of vibratory throw and will bring the upper or black field *a* opposite the printing point. As long as the concentric face 71 remains operative the throw of the vibrator will be a constant one and the types will follow a straight path lengthwise of the field *a*.

When it is desired to make use of the lower or red field *b*, the handle 88 is operated to bring the pointer 90 opposite the mark 60 "R", with the result that the controlling member is slid rightward on the shaft 46, causing the cone face 73 to operate on the actuating link and cam the latter forward against the pull of its spring 68, until said link is engaged by the concentric disk 70, at

which time the pin 64 will be at the forward end of the slot 63. In other words, the actuating link will now operate nearer the fulcrum of the operating lever and the arrangement is such that the longer throw thus 70 communicated to the ribbon carrier at printing operation will bring the lower or red field *b* opposite the printing point and cause the types to follow a straight path lengthwise of said field. 75

In the present construction it will be recalled that the platen is shifted for change of case and it will further be noted that the ribbon operating lever has a fixed and unvarying fulcrum. In order to compensate 80 for the shifting of the platen I provide means for enabling the ribbon carrier to be shifted automatically when the platen is shifted, this being accomplished by breaking the hinge-like or lock joint between the two parts of 85 the operating lever or more specifically in the present instance, by swinging the forward part 53 on the pivot connecting it with the rear part of the operating lever, said rear part remaining undisturbed during the 90 shifting of the platen and the movement of the part 53 on the pivotal center 57. The means employed in the present instance for breaking the joint and swinging the part 53 on the pivot 57, is shown clearly in Figs. 1, 95 3 and 4, and comprises a pin or lug 91 fixed to the arm 53 above the pivot 57 and extending upward therefrom. This pin enters a hole or opening formed in an extension or lip 92 curving upward and forward from a block-like member or slide 93. Said block-like member is slidably mounted on the arm or member 56 and is controlled by a connecting member or connection 94 horizontally disposed and pivoted at its forward end 100 on a shouldered screw 95 fixed to the slide 93. The inner face of the rear end of said connection 94 is formed with a longitudinally extending depression 96 which co-operates with the reduced end 62 of the screw 105 61, said end 62 serving to guide and support the said connection at its rear. A shouldered screw 97 is secured at the rear end of 110 said connection, and the shouldered or barrel portion of said screw 97 co-operates with a cam slot 98 formed at the upper or angled portion of a rigid arm 99, said arm inclining upward and rearward from the cross rod 35 and being provided with a collar portion 100 which fits over the rod 35 and is fixedly secured thereto by a set screw 101. The lower case position of the arm or member 99 is shown in Fig. 1, from an inspection 115 whereof it will be noted that the upper end of the slot 98 is at this time in co-operation with the screw or projection 97 on the connection 94 and that the slot 98 inclines downward and slightly rearward from said screw 97. When one of the platen shifting keys 120 40 is depressed to raise the platen shifting 125 130

frame and the platen it will operate to raise the arm 99 from the position shown in Fig. 1 to that shown in Fig. 3. During the upward movement of the arm 99 the forward edge 5 of the slot 98 will act against the shouldered portion of the screw 97, forcing the latter towards the rear and causing the connection 94 to move longitudinally rearward, the screw end 62 co-operating with the depression 10 96 to guide said connection. The rearward movement of the connection will operate to slide the block-like member or slide 93 rearward on the member 56, causing the extension 92 to pull against the lug 91 and 15 swing the forward lever part 53 upward on the pivot 57. Said lever part will carry with it the ribbon carrier and the printing portion of the ribbon so that the relation of the latter with the platen when the latter has 20 reached upper case position will be the same as its relation with the platen when the latter was in the lower case position.

Instead of pivotally mounting the connection 94 on the slide 93, said connection may 25 be rigidly secured to the slide. In Fig. 15 I have shown a modified construction in which the slide 93 is provided with an integral or rigid extension or connection 93^a carrying the screw 97. If preferred the modified construction of Fig. 15 may replace the corresponding construction shown in the other figures. Of course if the modified construction is employed no guide is needed for 30 the rear end of the connection 93^a.

The train of devices comprising the pin 91, 35 slide 93, connection 94, screw 97 and arm 99 not only operates as a shifting means to vary the relation between the two parts of the operating lever, but also operates to lock or 40 maintain said parts in either of the two relations which they bear to one another during vibratory printing movements, one of these relations being shown in Fig. 1 and the other in Fig. 3. It will be noted that when the 45 parts are related as in Fig. 1 the screw 97 is co-axial with the fulcrum of the operating lever, so that there will be no bodily movement of said screw during vibratory movements of said lever, but said screw will simply 50 rotate on its own axis. When the parts have been shifted to the positions shown in Fig. 3 the screw 97 having been moved backward away from the center of rotation will have a 55 slight bodily movement about said center during vibratory movements of the operating lever. To permit of this bodily movement the slot 98 has an extension below the screw 97 and arcuate in shape, the arc being struck from the center of rotation of the operating lever so that said screw may rotate 60 slightly about said center without interfering with the proper operation of the parts during their vibratory movements and without altering that relation between the two arms of 65 the operating lever shown in Fig. 3.

During the reshifting movement of the platen from upper to lower case the rear edge or wall of the slot 98 will operate against the screw 97 to force the connection 94 and slide 93 forward; said slide moving 70 along the arm 56 and the extension 92 of said slide operating on the lug 91 to swing the part 53 on the pivot 57 and restore it to the position shown in Fig. 1.

It will be noted that during the shifting 75 and reshifting movements the rear part of the operating lever, comprising the members 56 and 58, will not be affected and that consequently the relation between the slot 63 and the co-operating pin 64 will not be altered 80 or disturbed in any respect. Consequently the vibratory movements imparted to the operating lever by the actuating link 65—66 will be the same in extent after the shift of 85 the platen as before the shift, although of course the starting and stopping positions of the vibratory ribbon carrier and the printing portion of the ribbon will be altered by said shift by reason of the pivotal movement of the arm 53 on the center 57. These facts 90 will perhaps be more clearly apparent after a consideration of the diagrammatic views, Figs. 5-12 inclusive. Fig. 5 illustrates the normal relation between the platen and the printing portion of the ribbon when the 95 platen is in lower case position. Fig. 6 illustrates the printing position of the ribbon when the upper half of it is being used, or, in other words, when the pin 64 is at the rear of the slot 63, as illustrated in Fig. 1. Fig. 7 100 illustrates the normal relation between the platen and the printing portion of the ribbon after the platen has been shifted, while Fig. 8 shows the printing relation between the platen and the ribbon when the latter is in 105 shifted position and the upper half of the ribbon is being employed. Comparing Figs. 5 and 7 it will be noted that the relation between the platen and the printing portion of the ribbon is the same in both, although 110 their absolute positions have been varied. This last statement also applies to Figs. 6 and 8. Figs. 9-12 correspond respectively to Figs. 5-8 but with the lower half of the ribbon in use instead of the upper half. Fig. 115 9 shows the normal relation of the platen and ribbon in lower case position. Fig. 10 shows the printing relation of the platen in lower case position and the ribbon when its lower half is being employed. Fig. 11 shows the 120 normal relation of the platen and ribbon in upper case position, while Fig. 12 shows the printing relation between the platen in upper case position and the ribbon when the lower half thereof is being employed. It will 125 be noted that Figs. 9 and 11 show the same relation between the printing portion of the ribbon and the platen and that Figs. 10 and 12 show the same relation between the platen and the printing portion of the ribbon, but 130

the latter relation of course differs from the first relation. It will further be noted that the relation between the platen and the printing portion of the ribbon is the same in

5 Figs. 5, 7, 9 and 11. In other words, the normal relation between the platen and the ribbon is an unvarying one no matter whether the platen is in upper or in lower case or whether the lower or upper field of the ribbon is being made use of.

It will be noted that by my present invention I provide in combination with a shiftable platen and means for shifting said platen at will, a vibratory ribbon carrier or vibrator

15 which is shiftable with the platen so that said carrier has an unvarying normal relation with the platen; that the ribbon carrier is vibrated at printing operations by an operating lever which has a single fulcrum, said ful-

20 crum being non-shiftable and having the same normal position for both the shift positions of the platen; that said operating lever is in the present instance made in parts, the forward part of said lever, by which is meant

25 that part of the lever nearest to the vibrator, being connected to said vibrator and being movable therewith independently of the rear part of said lever, by which is meant that part of the lever furthest from the vibrator

30 or carrier; that means are provided for shifting said ribbon carrier or vibrator through said operating lever; that other means are provided for actuating the operating lever at printing operations, this actuating means be-

35 ing separate and distinct from the means which shifts the ribbon carrier; that additional means are provided for varying the relation between said separate actuating means and the operating lever in order to

40 vary the throw or vibratory movement of the ribbon carrier or vibrator at printing operations; that this variation in relation between the separate actuating means and the operating lever may be effected either auto-

45 matically or by hand, the automatic means including the eccentric disk and the draw spring which operates on the actuating link 65—66, said link of course being part of the separate actuating means, and the hand con-

50 trolled means comprising the two concentric disks and the slide rod and rock shaft for positioning said disks; that the forward part of the operating lever or that part nearest the vibrator or carrier is automatically shifted

55 by means connected with the platen shifting means so that said vibrator is simultaneously shifted with the shifting of the platen, the separate means for actuating said operating lever of course being operative both while

60 the platen is in lower case position and in upper case position; that the two parts of the operating lever are provided with a locking joint for holding or locking them in one or another relation, one of said relations being

65 the lower case or normal relation and the

other being the relation in which said parts are locked when the platen is in upper case position; that the operating lever is actuated as a whole at printing operations; and that only one part of said lever is moved to vary 70 the relation between the two parts, the moved part carrying the vibrator to a new initial position.

Various changes besides those specified may be made without departing from the 75 gist of my invention.

What I claim as new and desire to secure by Letters Patent, is:—

1. In a typewriting machine, the combination of a shiftable platen, a vibratory ribbon carrier shiftable with said platen and having an unvarying normal relation therewith, an operating lever having a single fulcrum, which fulcrum has the same normal position for both positions of the platen, 80 means for shifting said ribbon carrier through said operating lever, separate means for actuating said lever at printing operations, and means for varying the relation between said separate actuating means and said lever for varying the throw of said carrier.

2. In a typewriting machine, the combination of a shiftable platen, a vibratory ribbon carrier shiftable with said platen and 85 having an unvarying normal relation therewith, an operating lever having a single fulcrum which fulcrum has the same normal position for both positions of the platen, means for shifting said ribbon carrier through 90 said operating lever, separate means for actuating said lever at printing operations, and hand controlled means for varying the relation between said separate actuating means and said lever so as to cause said carrier to be 105 thrown one or another of a plurality of predetermined extents at printing operation.

3. In a typewriting machine, the combination of a shiftable platen, a vibratory ribbon carrier shiftable with said platen and having 110 an unvarying normal relation therewith, means for shifting the ribbon carrier with the platen, an operating lever having a single fulcrum which has the same normal position for both positions of the platen, means including a link for actuating said lever at printing operation, and means operating during the type strokes to automatically vary the relation between said lever and said link.

4. In a typewriting machine, the combination of a shiftable platen, a vibratory ribbon carrier shiftable with said platen and having an unvarying normal relation therewith, means for shifting the ribbon carrier with the 125 platen, an operating lever having a single fulcrum which has the same normal position for both positions of the platen, means including a link for actuating said lever at printing operation, and means operating au-

tomatically to vary the relation between said lever and said link, said automatic means including an eccentric coöperating with said link.

5. In a typewriting machine, the combination of a shiftable platen, a vibratory ribbon carrier shiftable with said platen and having an unvarying normal relation therewith, means for shifting the ribbon carrier with the platen, an operating lever having a single fulcrum which has the same normal position for both positions of the platen, means including a link for actuating said lever at printing operation, and means operating automatically to vary the relation between said lever and said link, said automatic means including an eccentric coöperating with said link, and a spring tending constantly to maintain said link in engagement with said eccentric.

6. In a typewriting machine, the combination of a shiftable platen, a vibratory ribbon carrier shiftable with said platen and having an unvarying normal relation therewith, means for shifting the ribbon carrier with the platen, an operating lever having a single fulcrum which has the same normal position for both positions of the platen, means for actuating said lever at printing operation, means operating automatically to vary the relation between the last recited means and said lever, and means for dispensing at will with said automatic means and for setting said actuating means in one or another of a plurality of predetermined normal relations with said lever so as to throw said lever one or another of a plurality of predetermined extents.

7. In a typewriting machine, the combination of a shiftable platen, a vibratory ribbon carrier shiftable with said platen and having an unvarying normal relation therewith, means for shifting the ribbon carrier with the platen, an operating lever having a single fulcrum which has the same normal position for both positions of the platen, means including a link for actuating said lever at printing operation, means operating automatically to vary the relation between said lever and said link, and means for dispensing at will with said automatic means and for setting said link in one or another of a plurality of predetermined normal relations with said lever, said last recited means including a plurality of concentric rotary devices shiftable transversely of said link to coöperate therewith.

8. In a typewriting machine, the combination with a shiftable platen, means for shifting the same, a ribbon vibrator, an operating lever therefor having a fixed fulcrum and said operating lever being made in parts, the forward part of said lever being connected to said vibrator and being movable therewith independently of the rear part of said lever,

means connected with the platen shifting means for automatically shifting the forward part of said lever and said ribbon vibrator simultaneously with the shifting of the platen, and means for actuating said operating lever while the platen is both in lower case and in upper case position.

9. In a typewriting machine, the combination of a vibratory ribbon carrier, a two-part operating lever, a lock joint for holding the two parts of said lever in one or another relation, and means for actuating said lever at printing operation to vibrate said ribbon carrier.

10. In a typewriting machine, the combination of a vibratory ribbon carrier, a two-part operating lever, means for actuating said lever as a whole at printing operations, and means operative on one part only of said lever to vary the relation between the two parts of said lever and to move the carrier to a new initial position.

11. In a typewriting machine, the combination of a vibratory ribbon carrier, a two-part operating lever, means for actuating said lever as a whole at printing operations, and means operative on one part only of said lever to vary the relation between the two parts of said lever and to move the carrier to a new initial position, said two parts of the lever being locked both in normal and in varied relation.

12. In a typewriting machine, the combination with a platen and platen shifting mechanism, of a vibratory ribbon carrier, a two-part operating lever, means for actuating said lever at printing operations, and means connected with said platen shifting mechanism and operative thereby to vary the relation between the two parts of said lever.

13. In a typewriting machine, the combination with a platen and platen shifting mechanism, of a vibratory ribbon carrier, a two-part operating lever the two parts of the lever being jointed together, means for locking the joint between said parts so as to hold them in one or another of a plurality of fixed relations depending on the shift position of the platen, and means for actuating said lever at printing operation.

14. In a typewriting machine, the combination of a vibratory ribbon carrier, a jointed operating lever, means for actuating said lever at printing operation, and means for changing the relationship between the jointed parts of said lever to vary the normal position of said carrier.

15. In a typewriting machine, the combination of a vibratory ribbon carrier, a jointed operating lever, means for actuating said lever at printing operation, and means for changing the relationship between the jointed parts of said lever to vary the normal position of said carrier and for maintaining the parts of the lever in set relations.

16. In a typewriting machine, the combination with a platen and platen shifting mechanism, of a vibratory ribbon carrier, a jointed operating lever, means for actuating said lever at printing operation, and means connected with and operative by said platen shifting mechanism to change the relationship between the jointed parts of said lever.
17. In a typewriting machine, the combination of a vibratory ribbon carrier, an operating lever having one part pivotally connected with said carrier, said part being connected with the other part of said lever by a joint, actuating means connected with said other part of said lever, and means for moving one of the parts of said lever to vary the initial position of the vibrator.
18. In a typewriting machine, the combination with a platen and platen shifting mechanism, of a vibratory ribbon carrier, a two-part jointed operating lever having one part pivotally connected with said carrier, an actuating link connected with the other part, and means connected with the platen shifting mechanism and operative to change the relationship between the jointed parts of said lever.
19. In a typewriting machine, the combination with a platen and platen shifting mechanism, of a vibratory ribbon carrier, a two-part operating lever therefor, said lever

having a fixed fulcrum and one of the parts of said lever being jointed to the other, an actuating link connected with the other part of said lever, a cam connected with said platen shifting mechanism, and means on said lever operative by said cam to break the joint in said lever.

20. In a typewriting machine, the combination with a platen and platen shifting mechanism, of a vibratory ribbon carrier, an operating lever therefor, said lever having a fixed fulcrum and comprising two parts, one of the parts being jointed to the other part, an actuating link connected with said other part, a cam connected with said platen shifting mechanism, means on said lever operative by said cam to break the joint in said lever, said last recited means comprising a movable member on one of the jointed parts of said lever, a device on the other jointed part of said lever engageable with said member, and a connection between said member and said cam.

Signed at the borough of Manhattan, city 55
of New York, in the county of New York, and
State of New York, this 14th day of March
A. D. 1908.

JACOB FELBEL.
